(57) **CLAIM**

The ornamental design for a charging case assembly for wireless earphones, as shown and described.

DESCRIPTION

FIG. 1 is a front perspective view of a charging case assembly for wireless earphones, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view

FIG. 8 is a bottom view thereof;

FIG. 9 is a perspective view of the charging case assembly for wireless earphones in an assembled orientation

FIG. 10 is a perspective view of the charging case assembly for wireless earphones in an assembled orientation with one side open,

FIG. 11 is a perspective view of the charging case assembly for wireless earphones in an alternative assembled orientation,

FIG. 12 is a perspective view of the charging case assembly for wireless earphones in an alternative assembled orientation with both sides open,

FIG. 13 is a perspective view of the charging case assembly for wireless earphones; and,

FIG. 14 is an enlarged detail view of area 14 in FIG. 1.

The broken lines in the drawings illustrate the portions of the charging case assembly for wireless earphones, which form no part of the claimed design.
